UNITED STATES PATENT OFFICE.

CHARLES W. BURGTORF, OF PETALUMA, CALIFORNIA.

SINGLE HARNESS.

SPECIFICATION forming part of Letters Patent No. 290,530, dated December 18, 1883.

Application filed July 5, 1883. (No model.)

To all whom it may concern:

Be it known that I, CHARLES W. BURGTORF, a citizen of the United States, residing at Petaluma, in the county of Sonoma and State of California, have invented certain new and useful Improvements in Single Harness, of which the following is a specification.

My improvement in single harness comprises, together with other parts, as hereinabove set forth, a buckle that is adapted for use in connection with a single girth, and serving the double purpose of a girth-buckle to connect with the gig-saddle and a bottom buckle to connect the girth with the straps which hold the shafts down, thereby dispensing with double girths and a multiplicity of buckles.

In the drawings which are hereunto annexed, and which form a part of this specification, Figure 1 is a perspective view, showing my improved buckle applied to the gig-saddle and girth of a set of single harness. Fig. 2 is a face view of the buckle and its connections. Fig. 3 is a detail view, showing the end of the girth, the buckle, and the shaft-strap. Fig. 4 is a longitudinal section through the buckle.

Similar letters of reference are used to indicate like parts throughout the several views.

A represents an ordinary gig-saddle, to which are attached the shaft-loops B and girth-straps C. The girth D is provided at each end with a single buckle, E, (the construction of which will be hereinafter more fully described,) and also a slotted pad or flap, F, which extends beyond the end of the girth, and occupies a position between the under or inner side of the buckle and the animal's body, and thus prevents chafing. The buckle connecting the girth with the other parts of the harness is made somewhat rectangular in plan, but with the upper portion or outer free end thereof curved upward, as shown in Fig. 4, in order that the said end may stand out somewhat from the animal's side.

About midway of the length of the buckle I place a transverse bar, a, having a suitable roller, upon which the point of the tongue b rests, while the heel thereof is bent around the rear or hinge bar, h, in the usual manner. The sides c c are united at the top by the curved bar d, and thus a loop, e, is formed in advance of the buckle proper, and adapted to receive the shaft-straps. The buckle and the

slotted pad F are then secured to the girth in the usual manner, and the shaft-strap G is secured to the outer end of the buckle, as clearly shown in Fig. 3. This last-named strap is an ordinary strap of the proper length, having a buckle, j, upon one end; but the fly or loose end f of the strap is made somewhat longer than usual, and while the main part of the strap is passed through the loop e the fly f is passed down upon the outside, and the two thicknesses are riveted together on either side of the top bar, d, by means of rivets g g, and thus the said strap G is held in place and prevented from slipping.

In practice I first pass the shafts through the shaft-loops B, and then pass the girth-strap C from the inside through the slot i in the pad F, and thence through the buckle, and confine it by means of the tongue b. The shaft-strap G is then passed up and lapped around the shaft on either side of the shaft-loop, as shown in Fig. 2, and brought down and passed through the buckle j, and thereby held in its proper position.

From the foregoing it will be seen that I am enabled to provide a means by which I dispense with the double girths in common use, and yet provide for the holding down of the vehicle-shafts and prevent their tilting upward beyond a certain regulated limit, as the same buckle which holds the gig-saddle and girth in place also serves as a hold-down buckle for the shaft-straps.

Having thus described my invention, what I claim, and desire to secure by Letters Patent, is—

In a single harness, the combination of the gig-saddle A, straps C C, girth D, shaft-straps G G, slotted pads F F, and the buckles E E, having a central cross-bar, a, provided with a roller, which forms a bearing for the tongue b, and a loop, e, for the reception of the shaft-straps, one of said buckles being placed at each end of the girth, all substantially as and for the purpose described.

In testimony that I claim the foregoing I have hereunto set my hand and seal.

CHARLES W. BURGTORF. [L. S.]
